UNITED STATES PATENT OFFICE.

AUBREY J. GRINDLE, OF CHICAGO, ILLINOIS, ASSIGNOR TO GRINDLE FUEL EQUIPMENT COMPANY, A CORPORATION OF ILLINOIS.

POWDERED-COAL APPARATUS.

Application filed July 29, 1919. Serial No. 314,136.

To all whom it may concern:

Be it known that I, AUBREY J. GRINDLE, a citizen of the United States of America, and resident of Chicago, county of Cook, and State of Illinois, have invented certain new and useful Improvements in Powdered-Coal Apparatus, of which the following is a specification, and which are illustrated in the accompanying drawings, forming a part 10 thereof.

The invention relates to apparatus for the use of powdered coal as fuel and has for its object the provision of improved means for obtaining a uniform regulated feed of 15 the comminuted fuel into a uniform and correspondingly regulated volume of air for delivery of the mixed air and fuel to a jet burner at the furnace.

In the accompanying drawings; 20 Fig. 1 is a detail side elevation of the apparatus showing the fuel hopper, blower, the air and fuel regulating devices and adjacent portions of the conduits leading to the furnaces;

25 Fig. 2 is a detail longitudinal sectional view taken centrally through the fuel feeding mechanism and the air regulator with adjacent portions of the conduit;

30 Figs. 3 and 4 are detail sectional views taken on the lines 3-3 and 4-4 respectively of Fig. 2, the face of one of two companion fuel plates being shown in Fig. 4; and

35 Fig. 5 is a face view of the other fuel feeding plate.

In the particular form of apparatus illustrated, the air blast and powdered fuel are respectively supplied to all the burners of one set, as those associated with a single furnace (not shown) from a common blower, as 11, and common fuel hopper 14. There are, however, separate fuel feeders and conduits for each burner but as these parts are generally of like construction for the different burners, the drawings and the following description are principally confined to apparatus which has for its function the maintenance and regulation of a powdered fuel supply for a single burner.

50 As shown, a motor 10 is directly connected to the blower 11, and is belted to a pulley, as 12, carried by the drive shaft, as 13, of a change speed gearing generally designated 15. This change speed gearing may

55 be of any well known type and the mecha-

nism of the same is not illustrated in detail. In the present construction it is employed for driving the fuel feeding screw 17. It follows that by movement of the controlling handle 16 of the change speed gearing the speed of the fuel feeding screw 17 may be varied while the speed of the shaft 13 remains constant. The delivery of fuel to each burner may thus be separately varied or discontinued entirely without changing the speed of the blower 11.

Screw 17 is mounted upon a shaft 19 and extends lengthwise through a casing 18 which preferably takes the form of a trough having a tubular outlet 18^a at one end but with the body portion of the trough constituting one compartment of the lower end of the powdered fuel hopper 14. Under these circumstances, the tubular outlet 18^a extends to and connects with an upright portion 23 of 75 the conduit leading to a single burner. For uniform delivery of the fuel I prefer to form the screw 17 with a plurality of threads, four being shown, and while the external diameter of the screw is preferably the same 80 throughout its length, the depth of the threads is desirably varied, as by reason of the tapering shape of the sleeve 20 upon which the threads are formed, the greatest depth of thread being adjacent the discharge end of the screw.

A pair of cooperating oppositely facing roughened plates 21, 22, one of them stationarily mounted adjacent the discharge end of the feed screw 17, the other plate revolving with shaft 19, are provided to break up compacted masses of the powdered fuel discharged by the feed screw 17 and to thereby further promote the delivery of the fuel at a uniform rate. That is to say, the provision of a plurality of the threads upon the feed screw 17 insures a substantially uniform discharge of the fuel by the frequent delivery of relatively small quantities or masses and the plates 21, 22, insure that these 100 quantities of fuel will be delivered to the air gradually rather than in the compact masses in which they might otherwise fall from the end of the screw. The plates 21, 22, are accordingly regarded as equalizer plates. 105

The distance between plates 21 and 22 may be adjusted by loosening the set screw 24, securing plate 22 to the shaft 19 and sliding the plate lengthwise on the shaft. When the separation of the plates 21, 22, has once 110

been adjusted to secure the best results it will not ordinarily be necessary to change this adjustment during use of the device. For convenience in separating the parts for inspection or repair I have shown a bushing 25 secured by means of set screws, as 26, within the tubular outlet portion 18^a of the casing 18. Upon removal of the bushing 25 a sleeve (not shown) of like size with the bushing but of greater length may be introduced about the feed screw 17 throughout its full length, thereby permitting removal and replacement of the feed screw without emptying the hopper 14. Furthermore, the bearing, as 78, in which the shaft 19 is journaled at its outer end, is carried by a removable plate 79, of larger size than the equalizer plate 22. Removal of plate 79 accordingly provides an opening in the wall 20 of the conduit portion 23 through which the equalizer plate 22, bushing 25 and feed screw 17 may be withdrawn.

A separate branch 27^a of the common blower outlet, as 27, connects with a valve casing 28, which valve casing is in turn connected with the lower end of the upright conduit portion 23. As shown, the valve casing 28 is cylindrical in form with its axis transverse to the axis of the conduit and with circular closed sides. The inlet and outlet openings of the valve casing 28 are substantially rectangular in shape, as indicated in Figs. 3 and 4. A convenient and compact arrangement of parts is provided if the valve casing 28 is supported immediately below casing 18 adjacent the outlet end of the same, as by means of companion lugs 29, 30, formed on said two parts, and connecting bolts 32.

Within the valve casing 28 is transversely mounted a valve gate 34 which is, in form, a portion of a cylinder and of a size to fit closely within the casing. Each end of the valve gate 34 is preferably formed with an inturned flange 35. These flanges are each provided with a trunnion 36 or 37, and each of these trunnions is centrally journaled in the adjacent circular side wall of the valve casing 28. As a means for manually adjusting the valve gate 34, one of the trunnions, as 37, extends beyond its bearing for the reception of an adjusting crank 38, and this crank carries a handle 39 and a pointer 40, which moves over a graduated scale 41. To prevent accidental derangement of the valve gate 34 the crank 38 may be provided with a bolt 49, traveling in a slot, as 43, and this bolt is constructed to be tightened in adjusted position by rotating the handle 39. Indicating buttons, as 44, preferably numbered to correspond with the numbering of the different positions of the controlling handle 16 of the change speed gearing 15, are adjustably located upon the edge of the scale 41, in accordance with previously determined positions of the valve gate to admit

the most desirable quantity of air to each conduit while the corresponding feed screw 17 is operating at each of the several speeds permitted by the said change speed gearing. The scale 41 is preferably also graduated to indicate the number of square inches of valve opening which correspond with the several positions of the pointer on the scale. After the buttons 44 are once adjusted upon the scale 41 it is only necessary, when feeding fuel at the rate provided by anyone of the speeds of the screw 17, to swing the pointer 40 to the button corresponding to that speed, when the most beneficial volume of air will at once be supplied by means of the air blast. As the blower 11 and feed screw 17 are driven by the same motor, as 10, these adjustments will be independent of the speed of the motor.

The upright portion 23 of the air conduit is preferably rectangular in cross section from its connection with the valve casing 28 to a point substantially above the level of the feed screw 17 and plates 21, 22. This is desirable both to provide room for the plates 21, 22, within the conduit and for the placing of the fuel into the blast to the best effect. A part of the air blast thus sweeps upwardly between plates 21, 22, thereby lifting the fuel in a direction opposite to that in which it would otherwise fall by gravity, and affording an additional means tending to promote a uniform delivery of the fuel into the air blast.

Connecting member 46, joining conduit 23 at flange 45, is rectangular at its lower portion and circular in its upper portion, thus changing from the rectangular form of conduit to the circular form, which produces better results through the elbow, as 47, or other necessary turns leading to the furnace. In the arrangement shown, elbow 47 of the conduit terminates with flange 48 for direct connection with another part, as 58, of the conduit, which may be the carbureter described and claimed in my concurrently filed application for patent in powdered coal apparatus, Case "B," Serial No. 314,137.

I claim as my invention:

In a powdered coal apparatus, in combination, a fuel hopper, a feed screw at the bottom of said hopper, a shaft carrying the screw and extending beyond the same at its delivery end, a stationary ribbed plate surrounding the feed screw at its said delivery end, a second ribbed plate carried by and revolving with said shaft and adjustably spaced from said first named plate, a conduit enclosing said plates, means for producing a blast of air in said conduit about and between the plates and in a direction parallel with the plane of the plates, and means for adjusting the volume of air in said blast.

AUBREY J. GRINDLE.
